(57) **CLAIM**

The ornamental design for a window cover with front and rear flaps, as shown and described.

DESCRIPTION

FIG. 1 is a front isometric view of a window cover with front and rear flaps of my new design;

FIG. 2 is a rear isometric view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The shading on the window cover with front and rear flaps is meant to delineate contour, not material or surface texture. The window cover with front and rear flaps is shown in FIGS. 12-19 with symbolic breaks in its length and width. The appearance of any portion of the window cover with front and rear flaps between the break lines forms no part of the claimed design.

The broken lines including, but not limited to those showing, the zipper tab, portions of the window cover, the window, and portions of the vehicle are for environmental purposes only and form no part of the claimed design.
